UNITED STATES PATENT OFFICE.

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 7, 1924. Serial No. 742,217.

To all whom it may concern:

Be it known that I, LESTER E. SPRAY, a citizen of the United States, residing at Wilkinsburg, in the county of Allegheny and State of Pennsylvania, have invented certain new and useful Improvements in Railway-Traffic-Controlling Apparatus, of which the following is a specification.

My invention relates to railway traffic controlling apparatus, and particularly to apparatus of the type comprising fixed signals located along the trackway and arranged to afford "three block" indication.

I will describe two forms of apparatus embodying my invention, and will then point out the novel features thereof in claims.

In the accompanying drawings, Fig. 1 is a diagrammatic view illustrating one form 20 of apparatus embodying my invention; Fig. 2 is a view showing a modification of the apparatus illustrated in Fig. 1 and also embodying my invention.

Similar reference characters refer to similar parts in both views.

Referring first to Fig. 1 the reference characters 1 and 1^a designate the track rails of a stretch of railway track over which traffic normally moves in the direction indicated by the arrow. These rails are divided, by means of insulated joints 2, into a plurality of successive track sections A—B, B—C, C—D, etc. Each track section is provided with a polarized track relay designated by the reference character R with a suitable distinguishing exponent and connected across the rails adjacent the entrance end of the corresponding section. Associated with each track relay R is an auxiliary relay designated by the reference character K with an exponent corresponding to the location. Each relay K is controlled by traffic conditions in advance as will be explained in detail hereinafter.

Each track section is provided with a trackway signal designated by the reference character S with an appropriate exponent. As here shown, each signal S is a three-position semaphore signal and is located adjacent the entrance end of the section which it governs, but this particular type and arrangement of signals is not essential to my invention. Three circuit controllers designated by the reference characters E, F and

G with exponents corresponding to the locations, and a pole changer designated by the reference character P with an exponent corresponding to the location, are operated by each signal S. Each circuit controller E, F and G is closed when the associated signal indicates caution or proceed, but open when the signal indicates stop. Each pole changer P is in normal position when the associated signal indicates caution or proceed, and in reverse position when the signal indicates stop.

Each relay K is at times supplied with energy from a suitable source such as a battery designated by the reference character L with an appropriate exponent, one of which batteries is provided for each section. Referring particularly to relay K^B, the circuit for this relay may be traced from battery L^c through wires 25, front contact 40 of relay R^c, wires 27 and 28, normal contact 29 of relay R^c, wire 30, circuit controller G^c operated by signal S^c, wire 31, winding of relay K^B, wire 32, front contact 33 of relay R^B, wires 45 and 34, circuit controller E^B operated by signal S^B, wires 35, 36 and 37, circuit controller E^c operated by signal S^c and wire 38 back to battery L^c. This circuit is closed, and consequently relay K^B is energized, only when relay R^c is energized in the normal direction, when relay R^B is energized, and when circuit controllers G^c, E^B and E^c are all closed. The circuit for each of the remaining relays K is similar to that just traced for relay K^B.

Each signal S is controlled by the associated track relay R and the associated auxiliary relay K in the following manner:

Referring particularly to signal S^B, when relay R^B is energized, current flows from battery L^B, through wire 39, front contact 40 of relay R^B, wires 41 and 42, operating mechanism of signal S^B, wire 43, front contact 33 of relay R^B, and wires 45 and 46 back to battery L^B; and under these conditions signal S^B indicates caution. Circuit controller F^B is then closed and if, under these conditions, relay K^B becomes energized, a circuit is closed from battery L^B, over wire 39, front contact 40 of relay R^B, wires 41, 47 and 48, front contact 49 of relay K^B, wire 50, circuit controller F^B operated by signal S^B, wire 51, operating mechanism of signal S^B, wire 43, front contact 33 of relay R^B,

and wires 45 and 46 back to battery L^B . When this circuit is closed, signal S^B indicates proceed. When relay R^B is de-energized signal S^B indicates stop.

5 Track circuit current of one polarity or the other is supplied to each section from a suitable source such as a track battery designated by the reference character 6 with an exponent corresponding to the location, 10 and the polarity of this current is controlled by the track relay R and the signal S for the section next in advance. Referring particularly to section A—B, when signal S^B is at caution or proceed and relay 15 R^B is energized, current flows from battery 6^B , through wire 16, pole changer P^B , wire 17, front contact 18 of relay R^B , wire 19 to rail 1 of section A—B and from rail 1^a of this section by wires 20 and 21, pole changer 20 P^B , wire 22, front contact 23 of relay R^B , wire 24, and resistor 7, back to battery 6^B . When this circuit is closed track circuit current of one polarity, which I shall hereinafter term "normal polarity", is supplied 25 to section A—B, and relay R^A is then energized in the normal direction, that is, in such direction as to close contact 29 thereon. If signal S^B indicates stop and relay R^B is de-energized, current flows from battery 30 6^B , through wire 16, pole changer P^B , wires 21 and 20 to rail 1^a of section A—B, and from rail 1 by wire 19, back contact 23 of relay R^B , wire 24, and resistor 7, back to battery 6^B . When this circuit is closed 35 track circuit current of the opposite polarity, which I shall call "reverse polarity", is supplied to section A—B and relay R^A is then energized in the reverse direction under which condition contact 29 is open.

40 I will now assume that relay R^B is de-energized but that signal S^B has stuck in the proceed or caution position. Current will then flow from battery 6^B through wire 16, pole changer P^B , wire 17, back contact 18 45 of relay R^B , wire 20 to rail 1^a, and from rail 1 through wire 19, back contact 23 of relay R^B , wire 24, and resistor 7 to battery 6^B . Section A—B is therefore supplied with track circuit current of reverse polarity.

50 As shown in the drawing, the section immediately to the right of point D is occupied by a train indicated diagrammatically at V. Relay R^D is therefore de-energized. Signal S^D then indicates stop, and 55 the circuit for relay K^C is broken at front contact 40 of relay R^D as well as at circuit controllers G^D and E^D . Pole changer P^D is reversed, and so track circuit current of reverse relative polarity is supplied to the 60 rails of section C—D. Relay R^C is therefore energized in the reverse direction and the caution operating circuit for signal S^C is closed at front contacts 33 and 40 of relay R^C , but the proceed operating circuit for this signal is open at front contact 65

49 of relay K^C . Signal S^C therefore indicates caution, pole changer P^C is normal, and circuit controllers E^C , F^C and G^C are all closed. Contact 29 of relay R^C is open however, and hence relay K^P is de-energized. 70 Track circuit current of normal polarity is supplied to section B—C, and relay R^B is therefore energized in the normal direction. Signal S^B indicates caution, and section A—B is supplied with track circuit current of 75 normal polarity. Track relay R^A is therefore energized in the normal direction and relay K^A is energized, thus completing the proceed circuit for signal S^A .

I will now assume that track relay R^D 80 is de-energized as shown in the drawing, but that signal S^D for some reason sticks in the proceed position. Pole changer P^D will then be in the normal position corresponding to the proceed indication of signal S^D , but by virtue of the arrangement of the circuits for battery 6^D the current supplied to section C—D by this battery is of reverse relative polarity. Signals S^C and S^B will then indicate caution and signal S^A will indicate proceed, exactly as though signal S^D were displaying the proper indication.

Referring now to Fig. 2, the apparatus is the same as that shown in Fig. 1 with the 95 exception of the control of the track battery 6. Referring again particularly to section A—B, the battery 6^B for this section is connected, through the usual resistor 7, directly to pole changer P^B . The contact 5 of pole changer P^B is connected, by wire 20, direct to rail 1^a of section A—B. Contact 4 of this pole changer is connected by front contact 23 of relay R^B and wires 53 and 19 with rail 1 of section A—B. Contact 100 4^a of pole changer P^B is constantly connected, by wire 54 and wire 19, with rail 1 of section A—B. It will therefore be plain that when relay R^B is energized, section 105 A—B is supplied with track circuit current of normal relative polarity if signal S^B indicates caution or proceed, and with current of reverse relative polarity if signal S^B indicates stop, whereas when relay R^B is de-energized, section A—B is supplied 110 with current of reverse relative polarity if signal S^B indicates stop but with no track circuit current if signal S^B indicates caution or proceed.

As shown in the drawing the section to 120 the right of point D is occupied as before by a train V. Relay R^D is therefore de-energized, and relay K^D is also de-energized. Signal S^D indicates stop, so that pole changer P^D is reversed, with the result that 125 section C—D is supplied with track circuit current of reverse polarity and relay R^C in the reverse direction. Relay R^C being energized, signal S^C indicates caution, so that track circuit current of normal polarity is 130

supplied to the rails of section B—C. Relay R^B is therefore energized in the normal direction, and signal S^B indicates caution, its proceed operating circuit being open at front contact 49 of relay K^B . Section A—B is therefore supplied with track circuit current of normal relative polarity and relay R^A is energized in the normal direction. The circuit for relay K^A is now closed at contact 29 of relay R^B and so signal S^A indicates proceed.

I will now assume that relay R^D is de-energized but that signal S^D for some reason sticks in the proceed or the caution position. The pole changer P^D will then be in the normal position so that the supply of track circuit current to section C—D will be completely interrupted. Relay R^C will therefore be de-energized and signal S^C will indicate stop. The consequent reversal of pole changer P^C will cause section B—C to be supplied with track circuit current of reverse polarity and relay R^B will be energized in the reverse direction. Signal S^B will then indicate caution. Signal S^A will also indicate caution and the signal at the entrance end of the section to the left of point A will indicate proceed.

With the apparatus illustrated in Fig. 2 a train approaching a signal which falsely indicates proceed receives a caution indication three track sections in the rear of the defective signal and a stop indication at the entrance of the first section in the rear of the defective signal.

Although I have herein shown and described only two forms of railway traffic controlling apparatus embodying my invention, it is understood that various changes and modifications may be made therein within the scope of the appended claims without departing from the spirit and scope of my invention.

Having thus described my invention, what I claim is:

1. In combination, a stretch of railway track comprising a plurality of track sections, a track relay for each section responsive to the polarity of the current supplied to the rails of the section, a signal for each section controlled in part by the associated track relay, and means controlled by each signal for supplying the section next in rear with current of one polarity when the track relay associated with such signal is energized and the signal displays one indication but effective when the relay is de-energized to reverse the polarity of such current irrespective of the indication displayed by such signal.

2. Railway traffic controlling apparatus comprising a plurality of successive sections of railway track, a track relay for each section responsive to the relative polarity of the current supplied to the rails of the section,

a signal for each section, and controlling means for each signal including the associated track relay and so arranged that each signal normally indicates proceed but that when a section is occupied the corresponding signal indicates stop and the first and second signals in rear thereof indicate caution; the combination with the aforesaid instrumentalities of means controlled by each said signal and the associated track relay and effective when the track relay is de-energized and the associated signal indicates proceed to cause the two signals next in rear to indicate caution.

3. In combination, a forward and a rear section of railway track, a track relay for said forward section, a signal controlled in part by said relay, a source of track circuit current for said rear section, a pole changer operated by said signal for controlling the polarity of the current supplied to said rear section from said source, means comprising contacts on said relay for at times removing said pole changer from the control of said source, and traffic governing means responsive to the polarity of the track circuit current supplied to said rear section.

4. In combination, a forward and a rear section of railway track, a track relay for said forward section, a signal controlled in part by said relay, means effective when said relay is de-energized for supplying said rear section with track circuit current of one polarity irrespective of the condition of said signal but effective when such relay is energized for controlling the supply of track circuit current to said rear section in accordance with the indication displayed by said signal, and traffic governing means responsive to the polarity of such current.

5. In combination, a forward and a rear section of railway track, a track relay for said forward section, a signal controlled in part by said relay, a pole changer operated by said signal, a track battery, means effective when said relay is energized for connecting the terminals of said battery with the two rails respectively of said rear section through said pole changer, and means effective when the relay is de-energized for connecting one terminal of the battery directly with one rail of said rear section and for connecting the other terminal of the battery to the remaining rail of said rear stretch directly or through a back contact of said relay, depending upon the position of said pole changer.

6. In combination, a forward and a rear section of railway track, a track relay for said forward section, a signal controlled in part by said relay, a pole changer operated by said signal, a track battery, means controlled by said relay and by said pole changer for at times supplying current of one polarity to the rails of said rear section

from said source and means controlled solely by said pole changer for at other times supplying current of the other polarity to said rear section from said source.

- 5 7. In combination, a forward and a rear section of railway track, a track relay for said forward section, a signal controlled in part by said relay, a pole changer operated by said signal, a track battery, means effec-

tive when said pole changer is reversed for connecting said battery directly with the two track rails of said rear section and for reversely connecting said battery with said rear section over a front contact of said relay when said pole changer is normal. 10 15

In testimony whereof I affix my signature.

LESTER E. SPRAY,
